[57] CLAIM

The ornamental design for a slicing machine for magnetic tape or the like, substantially as shown.

DESCRIPTION

FIG. 1 is a perspective view of a slicing machine for magnetic tape or the like showing our new design;

FIG. 2 is a right side elevational view thereof;

FIG. 3 is a front elevational view thereof;

FIG. 4 is a left side elevational view thereof;

FIG. 5 is a top plan view thereof; and

FIG. 6 is a rear elevational view thereof.

FIG. 1

FIG. 2

FIG. 3

FIG. 4

FIG. 5

FIG. 6
